UNITED STATES PATENT OFFICE.

JESSE A. CRANDALL, OF BROOKLYN, NEW YORK, ASSIGNOR TO IVES,
BLAKESLEE & CO., OF BRIDGEPORT, CONNECTICUT.

TOY WHEELBARROW.

SPECIFICATION forming part of Letters Patent No. 253,846, dated February 21, 1882.

Application filed January 11, 1882. (No model.)

To all whom it may concern:

Be it known that I, JESSE A. CRANDALL, of Brooklyn, in the county of Kings and State of New York, have invented a new and Improved 5 Toy Wheelbarrow, of which the following is a specification.

Figure 1 is a perspective view of my improved toy wheelbarrow. Fig. 2 is a top view of the same.

10 This invention relates to a new toy wheelbarrow, which is made with side pieces in form of animals, or analogous form, each in one piece. By this means amusement may be afforded to children, and I obtain the further advantage 15 of making each side of the wheelbarrow, including the cheek-piece, the axle-support, the rear rest, and the handle, in one piece, and other advantages that are hereinafter more fully described.

20 In the drawings, A is the bottom of the wheelbarrow; B, the front board. C C are the side pieces. D is the axle, and E the wheel. Each side piece C is made in form of a horse or other animal, or of other analogous 25 form, of a board or plate of proper strength. The front legs, a, of said animals constitute the supports for the axle D, the hind legs, b,

the rear supports of the wheelbarrow. The tails d are the handles, the bodies e the cheek-pieces of the wheelbarrow, and the heads f will 30 furnish supports when the wheelbarrow is to be placed aside in an upright position—i. e., with the handles projecting upward.

The side piece C can be fastened to the bottom A and front B by screws g. This will 35 permit the convenient packing of the article during transportation.

I claim—

1. A wheelbarrow having each cheek-piece e, handle d, rear rest, b, and axle-support a 40 made in one piece, C, substantially as described.

2. A wheelbarrow having each cheek-piece, handle, rear rest, axle-support, and front projection, f, made in one piece, C, substantially 45 as described.

3. As a new article of manufacture, a wheelbarrow having its sides constructed in form of animals, substantially as and for the purpose herein shown and described.

JESSE A. CRANDALL.
